BOX FOR PERFUME BOTTLES OR SIMILAR ARTICLES

Eric de Kolb, New York, N. Y., assignor to Coty, Inc.,
New York, N. Y., a corporation of Delaware

Application March 4, 1957, Serial No. 45,056

Term of patent 14 years

(Cl. D58—13)

Fig. 1 is a perspective view of a box for perfume bottles or similar articles showing my new design;

Fig. 2 is a perspective view thereof shown in open position;

Fig. 3 is a side elevational view thereof; and

Fig. 4 is a top plan view thereof shown in open position.

I claim:

The ornamental design for a box for perfume bottles or similar articles, substantially as shown.
